UNITED STATES PATENT OFFICE.

WALTER D. PARKER, OF ROME, GEORGIA, ASSIGNOR OF ONE-THIRD TO LEONARD F. McKOY,
OF ROME, GEORGIA.

MUSIC-LEAF TURNER.

No. 923,440.

Specification of Letters Patent.

Patented June 1, 1909.

Application filed May 14, 1908. Serial No. 432,871.

To all whom it may concern:

Be it known that I, WALTER D. PARKER, a citizen of the United States, residing at Rome, Floyd county, Georgia, have invented 5 certain new and useful Improvements in Music-Leaf Turners; and I do hereby declare the following to be a full, clear, and exact description of the invention, such as will enable others skilled in the art to which it app- 10 pertains to make and use the same.

This invention relates to improvements in leaf turners, and more particularly relates to vices for turning the pages or leaves of music books or sheets; and the objects and nature 15 of my invention will be readily understood by those skilled in the art in the light of the following explanation of the accompanying drawings which illustrate what I now consider my preferred embodiment from among 20 other forms, arrangements and constructions within the spirit and scope of my invention.

The invention consists in certain novel features in construction and arrangements and combinations of parts as more fully and par- 25 ticularly set forth hereinafter.

Referring to the accompanying drawings;—Figure 1, is a front elevation of a leaf turner constructed in accordance with my invention. Fig. 2, is a vertical section. Fig. 30 3, is a top plan view. Fig. 4, is a horizontal section. Fig. 5, is an enlarged plan view of one of the leaf blade slides, showing a portion of a turning arm. Figs. 6 and 7, are detail 35 views illustrating the leaf blade slide, the locking cam lever thereof not being shown in Fig. 6. Fig. 8, is a detail view illustrating the vertical series of detents and the pivot and stop rods thereof. Fig. 9, is a detail 40 view illustrating the foot pedal operated air compressor.

In the drawings, 1, is a suitable elongated base having the upright standards 2, having brackets or shoulders 3, constituting a book rack to carry and support the music book or 45 sheets in open or flat position for easy reading and inspection by the performer. If so desired, the standards at their upper ends can be provided with clips or any other suitable means for holding the book back. 50 However, I do not wish to limit my invention to any particular construction of base or of book support or rack as any suitable means can be provided for holding the music book or sheets in the desired displayed posi- 55 tion and adjustment. Any suitable portable

folding or other rack or stand can be employed, or the musical instrument can be provided with the usual or with any suitable book or sheet holder or rack.

In the specific example illustrated, a base 60 plate 4, is secured on the base 1, and on this plate is arranged a vertical series of concentric independently rotatable superimposed horizontal disks 5; and 6, is a horizontal top head or plate arranged above said series of 65 disks.

The two heads or plates 4, 6, are secured together and held spaced the desired distance apart by vertical bolts 7, arranged exteriorly of the disks and, if so desired, having adjustable nuts 8, at the upper and lower faces of the head or plate 6, whereby said plate can be adjusted vertically to take up wear between the rotary disks or for other purposes. 75

The disks are spaced apart and from the fixed end heads 4, 6, to permit the separate and independent rotation of each disk, by any suitable means, although in the drawings, I show the disks separated from each 80 other and from the end heads 4, 6, by annular series of loose anti-friction balls 9, confined in annular ball race-ways or grooves in the upper and lower faces of each disk and in the opposing faces of the heads 4, 6. 85

In its open center, each disk is provided with a coiled impelling spring 10, at one end secured to the disk and at the opposite end secured to a center post 11, passing centrally through the disks and normally held stationary with respect to the disks. Thin washers 12, centered on said post can be interposed between the open centers of the adjacent disks for the purpose of separating the springs and preventing displacement and telescoping thereof. Suitable means can be provided for varying the tension of the disk impelling springs. For instance, I show the post 11, passing through and mounted to turn in the upper head or plate 6, with its 100 projecting upper end squared or otherwise formed to receive a key by which the post can be rotated to tighten all of the disk-impelling springs. At its lower end the post is provided with a pawl and ratchet mechanism 13, usually arranged in a depression in the upper face of base plate or head 4, to hold the post against retrograde rotation under tension of the disk impelling springs. 105

The disk impelling springs are preferably 110

so arranged as to constantly tend to rotate the disks from right to left, and each disk is provided with a radial turning arm 14, extending horizontally or about horizontally 5 from the edge thereof. If so desired, each arm 14, can be secured in the slot of a lug 15, rigid with and projecting radially from the periphery of its disk.

At its outer or free end, each radial or turning arm is provided with a vertical or upwardly projecting leaf or page engaging blade 16, adapted to rest beneath a page or leaf and turn the same from right to left as will be easily understood by those skilled in 15 the art.

I usually provide means whereby each leaf blade can be adjusted longitudinally of the turning arm carrying the same, and if so desired whereby said blade can be swung or 20 folded downwardly to a horizontal or approximately horizontal in-operative or out of the way position. To this end, I arrange a slide 17, on each arm capable of sliding longitudinally thereof and of slipping on and 25 off the free end of the arm. At the front side of this slide, I fulcrum a laterally or horizontally swinging locking or cam lever 18, normally locking the slide to the arm and adapted to be swung outwardly, as shown 30 by dotted lines, to inoperative position to release the slide and permit the same to slide in either direction along the arm.

The slide projects upwardly from its lower portion embracing the arm and is vertically 35 slotted or bifurcated to receive the lower end of the blade which is mounted in said bifurcation on transverse pivot 20 to permit vertical swing of the blade from an outwardly extending horizontal position to the vertical 40 operative position, or vice versa. The blade is yieldingly held when in operative and inoperative positions by a vertically disposed flat spring 22, carried by the slide and at its free end bearing against the edge of the lower 45 end 21, of the blade, which edge of end 21, can be formed with flat faces to engage the spring when the blade is in vertical and horizontal positions.

Any suitable or desirable number of leaf 50 turning arms and their carrying and impelling disks can be employed and where several arms are employed they are swung to operative position, against the tension of their impelling springs, with the blades behind 55 the successive advance pages respectively, which are to be successively turned as the reading or musical performance progresses, as will be understood by those skilled in the art.

Means are provided to hold each arm in its 60 operative position against the tension of its impelling spring, and means, under the control of the performer or operator, are provided for successively or one at a time, releasing 65 said arms independently of the re-

maining locked arms to permit the impelling spring thereof to swing the arm and the page or leaf in front of its blade around through an arc of about one hundred and eighty degrees to expose the reverse side of the leaf or 70 sheet and the front side of the next succeeding leaf.

In the specific example illustrated, I show the edge or circumferential portion of each disk formed or provided with a curved about 75 radial locking shoulder, projection or tooth 23, adjacent to and a short distance behind its arm carrying lug or ear 15, and adapted to be engaged with a horizontally swinging eccentric or cam locking lever, dog, detent or trigger. A detent is provided for each disk and the detents of the vertical series are fulcrumed or pivoted on a common vertical pin or post 25, arranged between the top and bottom plates 4, 6, and arranged just beyond 85 the disks and a short distance in rear of the arm carrying lugs 15, when the arms and disks are in operative position.

Each detent is formed with the elongated outwardly projecting usually straight end 24, 90 and with the rounded cam locking head or end 26, having a disk-engaging edge or surface arranged eccentrically with respect to the fulcrum pin or post 25. The arrangement is such that when the disk is in operative position, it can be locked and held in such position by swinging the long end 24, of the detent rearwardly thereby swinging its cam end 26, into engagement with the disk edge at the front edge of the locking tooth or shoulder, and thereby holding the disk in operative position against the tension of its spring. After the series of turning arms have performed their leaf turning strokes, they are swung by hand back to operative 100 position and can be there held as the detents are swung, by the fingers engaging long ends 24, to locking position. The turning arms are released one at a time to perform their operative strokes, usually beginning with the 105 upper or top arm of the series, by successively swinging forwardly the projected ends 24, of the detents and thereby moving the cam head of each detent rearwardly and outwardly clear of and from engagement with 110 the tooth or shoulder 23, of its particular disk, permitting the disk to rotate under the impulse of its spring independently of the remaining disks.

I provide means, under the control of the 115 operator, for successively swinging outwardly the free ends 24, of the vertical series of detents. For instance, in the particular example illustrated, I have provided pneumatic means for releasing the detents comprising actuating mechanism, such as a foot 120 pedal operated air compressor, for transmitting force or movement to a plunger for successively swinging and releasing the detents, means being provided whereby this plunger 125 130

successively moves into operative relation or position with respect to the separate detents. To this end, I show a horizontally disposed vertically movable cylinder 27, at its rear 5 end provided with and closed by the hollow nipple 28, coupled to the usually flexible air tube 29, leading from the foot operated air compressor to be hereinafter described. At its front end this cylinder is formed with a 10 forwardly projecting nose, projection or guide 30, adapted to successively rest on the free ends of the detents when in locking position. 31, is a piston in said cylinder yieldingly held to its limit of rearward movement 15 by spring 32, with its piston rod or plunger 33, in its normal position withdrawn into the front end or head of the cylinder, from below the guide or nose 30. When an impulse of air under the necessary pressure is forced 20 through tube 29, the piston is driven forward thereby projecting the plunger longitudinally along the under surface of the nose 30, and striking and swinging forward the free end of the detent on which said nose rests, 25 thereby throwing the detent from locking position and releasing the disk and turning arm held thereby. Under the pressure of spring 32, the piston is immediately returned to normal position and the plunger is with- 30 drawn from under the nose.

The cylinder is vertically movable by gravity and is upheld by its nose 30, resting on a detent when in locking position. When all of the detents are in locking position, the 35 cylinder nose rests on the topmost detent, and on swinging this detent forwardly to release the same, the cylinder automatically drops therefrom to the next detent below and so on throughout the entire series of 40 detents, and when the bottom detent has been released, the cylinder reaches its limit of downward movement, and is then lifted by hand, or in any suitable manner, to its topmost position to permit return of the 45 detents to locking position and to assume its position upheld by and resting on the topmost detent.

Any suitable means can be provided for permitting the vertical movement of the 50 cylinder and for guiding the same in its movement. For instance, I show a vertical guideway for the cylinder formed by a pair of longitudinally grooved spaced vertical posts or standards 34, at their lower ends 55 suitably affixed to the base and at their upper ends secured to a bracket 35, extending laterally from and secured to the top plate or head 6. The cylinder is received between said posts and is provided with lateral lugs 60 or projections 36, fitting loosely and slidably vertically in the grooves of said posts.

In the specific example illustrated, I show 65 an air compressor consisting of bellows secured to a piano front board 37, below the key board, and having the flexible air tube

29, coupled thereto to form the compressed air outlet therefrom. In the particular form of bellows disclosed, one head thereof is secured to the front board 37, while the movable head 38, is connected thereto by the 70 flexible bellows sides 39, and the lower ends of the bellows heads are pivotally joined by spring hinge 40, constantly tending to swing head 38, outwardly to expand the bellows.

A lever is provided for compressing the 75 bellows to produce the momentary impulse or air pressure necessary to project the detent throwing plunger. This lever is fulcrumed at 41, intermediate its length and has the exterior foot pedal 42, while the inner end of the lever extends upwardly at the outer or rear face of the movable bellows head and is provided with anti-friction roller 43, in engagement therewith. When the foot 80 pedal is depressed, the inner upwardly extending end of the lever forces the bellows head inwardly to compress the bellows and produce the desired momentary air pressure.

I do not wish to limit all features of my invention to any particular description of 90 means for actuating the piston actuated releasing plunger, and where my leaf turner is employed in connection with a music rack or stand, if an air compressor is employed, it can be otherwise constructed or arranged 95 than illustrated in the accompanying drawings, and if the bellows be employed, the compressing lever can be dispensed with.

Where the pivoted blades 16, are employed, the turning arms can be locked in 100 operative position and all of the blades swung down to inoperative position, to permit location of the music book on the rack or support, and the blades can then be swung up to operative position respectively 105 between the proper or desired leaves of the book to turn the pages successively in proper order, while the blades can be adjusted longitudinally on the arms according to the size 110 of the book or to locate each blade in the particular position desired with respect to the remaining blades.

Instead of pressing the detents back to locking position by hand, I can provide each 115 radial arm 14, with a rearwardly springing yielding finger 140, at its free rear end adapted to engage the free end of the detent belonging to said arm. When an arm is swung to the right to operative position its spring finger 140, will engage the forwardly 120 swung detent of said arm and press said detent back to locking position. The arms can all be swung back together and the spring fingers will press the detents to position locking said arms in operative position. 125 A vertical stop rod 141, can be provided to limit the rearward swing of the detents.

If so desired, each leaf blade slide can comprise a pair of right angle plates having their 130 parallel vertical portions secured together

with the spring 22, and leaf blade between them. The lower horizontal portions of said angle plates are spaced apart to receive the arm 14, between them. The spring cam 5 lever 18, is arranged between the outer ends of said horizontal portions of said plates and are confined therein by and turn on the pivot pin 180. In the specific example illustrated, I show a spring or yielding plate or 10 finger 181, arranged approximately parallel with the radial arm 14, on which the slide is longitudinally adjustable, and the free end of this spring finger yieldingly bears against the side face of said arm and is interposed 15 between the same and the cam head of locking lever 18, so that when in locking position, Figs. 5 and 7, the lever presses and clamps said finger against the arm to lock the slide thereto. I show the spring finger 181, carried 20 by, integral with, bent down and partially severed from a horizontal plate or body portion 182, secured on the top horizontal portion of one of the angle plates of the slide.

It is evident that various changes and 25 modifications might be resorted to, that elements might be omitted, or features or constructions added, without departing from the spirit and scope of my invention, hence I do not wish to limit myself in all respects to the 30 constructions disclosed.

What I claim as new and desire to secure by Letters Patent of the United States is:—

1. A leaf turner comprising a series of independently swingable turning arms provided with leaf engaging means and with impelling mechanism, means for holding said arms in operative position against the impelling force of said mechanism, yielding contacts between said arms and said arm- 35 holding means for returning said means to arm-holding position by the backward movement of said arms to operative position, and pneumatically actuated means for successively releasing the holding means of said 40 arms and thereby permitting the arms to successively perform their operative strokes.

2. A leaf turner comprising a series of independently rotatable spring impelled disks each provided with a turning arm having 50 leaf engaging means, a series of independent disk holding detents, each detent adapted to hold its disk in operative position against the tension of its impelling spring, detent-releasing means comprising a movable carrier and 55 a plunger common to all of said detents and adapted to successively move from detent to detent and thereby successively release the same to permit said arms to successively perform their operative strokes, and manually 60 controlled actuating means for said plunger.

3. A leaf turner comprising a spring impelled swinging turning arm provided with leaf engaging means, a movable detent for holding said arm in operative position, a pressure actuated plunger for moving said detent 65

to release said arm, a spring contact between said arm and said detent for returning the detent to locking position, and manually controlled fluid compressing means for actuating said plunger. 70

4. A leaf turner comprising a series of spring impelled swinging superimposed turning arms provided with leaf engaging means, a series of movable detents, one for each arm for holding the same in operative position 75 against the tension of its spring, yielding contacts between the arms and their said detents for returning the detents to arm-holding position by the backward movement of the arms to operative position, and a manually controlled detent releasing device 80 common to all of the detents and adapted to separately operate the same one at a time, substantially as described.

5. A leaf turner comprising a series of spring impelled independently swinging turning arms mounted on a common axis and provided with leaf engaging means, a series of independent movable detents, one for each arm for holding the same in operative position 85 against the tension of its spring, and a vertically movable detent releasing device common to all the detents and resting on and upheld by the topmost detent in locking position, and adapted to drop from detent to 90 detent to separately and successively move the same to release the arms held thereby.

6. A leaf turner comprising a base having a head fixed thereto, and an opposing head fixed to said first mentioned head, a series of 100 independently rotatable superimposed disks arranged between said heads, a post arranged centrally within all the disks and mounted in and projecting through one of said heads, said post provided with pawl and ratchet 105 mechanism for holding the same against retrograde rotation, impelling springs for said disks, each spring at one end confined to its disk and at the opposite end confined to said post, each disk provided with a turning arm 110 having leaf engaging means, and a series of disk holding detents, one for each disk, and detent releasing means.

7. A leaf turner comprising a spring impelled rotary disk having a radial turning 115 arm provided with leaf engaging means, said disk provided with an edge locking tooth or shoulder, a disk locking detent fulcrumed intermediate its ends exteriorly of the disk and provided with a cam locking head adapted to swing into and out of locking engagement with said tooth, said arm provided with a detent-setting spring contact and detent releasing means adapted to swing the detent to release the disk. 120

8. A leaf turner comprising a series of superimposed spring impelled independently rotatable disks, each provided with a turning arm having leaf engaging means, and with an exterior edge locking tooth or shoulder, and a 130

series of superimposed independent swinging detents mounted exteriorly of the disks to turn on a common axial line and having free ends and cam locking heads adapted to move into and from locking engagement with said disk teeth, a plunger for successively engaging and swinging said detents to release said disks, a movable carrier for said plunger, and pneumatic actuating means for said plunger.

9. A leaf turner comprising a series of spring impelled independently swingable turning arms having leaf engaging means, a series of independent superimposed movable detents, one for each arm for holding the same in operative position, and detent releasing means comprising a vertically movable cylinder adapted to rest on and be upheld by the topmost detent in holding position, and to drop down by gravity from detent to detent as the same are moved from holding position, a detent moving plunger carried by said cylinder, and means for actuating said plunger.

10. A leaf turner comprising a series of swinging leaf turning arms provided with leaf engaging means, a series of detents, one for each arm, for holding the same in operative position, and detent releasing means

comprising a vertically movable cylinder 30 adapted to be upheld by the upper one of said detents, a piston in said cylinder provided with a detent moving plunger adapted to separately engage and move the detents successively from holding position, and 35 manually controlled air compressing means connected with said cylinder.

11. A leaf turner comprising a series of leaf turning arms having leaf engaging means, a vertical series of independent detents, one for each arm, a vertically movable cylinder having a nose adapted to rest on and be upheld by each detent successively, vertical guideways receiving said cylinder and maintaining the same to slide vertically 45 therein, a piston in said cylinder provided with a plunger to project beneath said nose to successively engage and move the detents separately, means to normally maintain said plunger in withdrawn position, and a manually controlled air compressor connected with said cylinder.

In testimony whereof I affix my signature, in presence of two witnesses.

WALTER D. PARKER.
